UNITED STATES PATENT OFFICE.

FREDERIC L. WARD, OF DETROIT, MICHIGAN.

HYDRAULIC CONVEYER.

Application filed April 1, 1924. Serial No. 703,444.

The invention relates to apparatus for hydraulically conveying sand and gravel from one point to another and consists in certain improvements which enable a maximum load to be conveyed with a minimum power output, and this results in a greater efficiency than with the present type of apparatus.

In the present state of the art, it is usual 10 to employ a sand sucker for drawing in the sand and gravel from the river bed or other starting point of the system, the material then passing through a rotary pump and finally travelling through the outlet conduit 15 to the point of deposit. With this arrangement it frequently happens that the inlet becomes choked up due to the character of the material adjacent thereto, thereby decreasing the velocity through the conduit 20 which tends to cause the load to drop out of suspension. For this reason it is necessary to provide excess power in the pump for any given system to insure the proper functioning of the conveyer under all conditions 25 of operation without danger of the dropping of the load.

In my improved apparatus I have devised a hydraulic conveyer system designed to prevent any possibility of dropping the load, while at the same time utilizing a minimum amount of power for conveying the material to any predetermined distance. This has been accomplished by introducing the sand and gravel into the conveyer conduit by auxiliary means, thereby eliminating the sucking of the material through the pump and the consequential fluctuation of the velocity in the delivery conduit. In my preferred form of device the solid material 30 is introduced into hoppers communicating with the hydraulic delivery conduit through valve controlling apertures, these hoppers being provided with sealing covers and with means for introducing an auxiliary stream 35 of water to aid in the feeding of the material to the main conduit. This construction is more fully hereinafter described and illustrated in the drawings, in which—

Figure 1 is a diagrammatic view of the 40 hydraulic system; and

Figure 2 is a cross section taken on the line 2—2 of Figure 1.

The centrifugal pump A is provided with the inlet conduit B and the outlet conduit C, 45 the latter extending for whatever distance over which the conveyer system is designed

to operate. This conduit is also of substantially uniform cross sectional area and unobstructed throughout its entire length, thereby allowing the fluid passing therethrough to have a substantially constant velocity. Above the conduit C are arranged a plurality of hoppers D and D' communicating with the conduit through the passageways E and E', the latter being preferably 50 inclined to the direction of flow through the conduit C in order to cause a suction within the hoppers due to the velocity of flow through the conduit. The passageways E and E' are preferably controlled by valves F and F', while the hoppers are provided with covers G and G' hingedly connected to the hoppers at H and H' and adapted to seat upon the respective flanges I and I' to seal the hoppers. In order to aid in introducing the solid material from the hoppers into the main conduit C I have provided the branch conduit J leading from the pump A and communicating with the respective hoppers through the branches J' and J'', 60 both of which are controlled by suitable valves K and K'.

With the arrangement as described, the pump A is constantly delivering fluid through the conduit C during the operation of the system and the sand and gravel or other solid material is alternatively delivered to the hoppers, the hopper receiving the material having the cover in open position and the valve in closed position, while 70 the other hopper previously filled with material has the cover closed and the valve open. With this arrangement the solid material is drawn into the conduit C through the passageway E, while the water is delivered to the upper portion of the hopper through the conduit J'. As soon as one hopper has been emptied and the other hopper filled the valves F and K are closed while the valves F' and K' are opened, and 75 the cover G is open while the cover G' is closed. The material will then be fed to the conduit through the passageway E', while the hopper D may be filled with gravel by any suitable auxiliary feeding mechanism 80 such, for instance, as the ordinary scoop bucket dredge.

The system, as outlined above, has been found to be more practical than the usual sand sucker for it enables a larger amount 85 of material to be conveyed with a certain sized pump, and since the liquid is forced

through the delivery conduit at a constant rate, there is no tendency for the material to drop out of suspension and interfere with the proper functioning of the apparatus.

5 It will be noted that the conduit C is unobstructed through its entire length, and this permits the maximum flow of water for a certain size pumping mechanism.

What I claim as my invention is:—

- 10 1. In a hydraulic system for conveying material in suspension, the combination with a pump, of an unobstructed delivery conduit for said pump, a plurality of hoppers communicating with said conduit at longitudinally spaced portions thereof, valves for said hoppers, covers for sealing said hoppers, and valve controlled conduits leading from said water pump to the respective hoppers.
- 15 2. In a hydraulic system for conveying material in suspension, the combination with a pump and an unobstructed delivery conduit extending therefrom, of a plurality of hoppers, each communicating with said conduit through a passageway inclined to the direction of flow through said conduit, said passageways communicating with said conduit at longitudinally spaced points thereof, means for introducing liquid into
- 20 30 the upper portion of said hoppers, and covers for said hoppers adapted to seal the same when in closed position.

3. In a hydraulic system for conveying material in suspension, the combination with an unobstructed main conduit and means for flowing water therethrough at a substantially constant velocity, of a pair of hoppers, connecting conduits extending between said hoppers and said main conduit inclined in the direction of flow through the latter, said connecting conduits communicating with said main conduit at longitudinally spaced points thereof, means for sealing said hoppers, a water supply conduit communicating with each hopper and valves in said connecting conduits for preventing communication with said main conduit when said hoppers are unsealed and for permitting communication with said main conduit when said hoppers are sealed.

4. In a hydraulic system for conveying material in suspension, the combination with an unobstructed conveyer conduit, of means for flowing liquid therethrough at a substantially constant velocity, a plurality of hoppers for solid material communicating with said conduit at longitudinally spaced points thereof, valves associated with said hoppers for controlling the communication of the same with said conveyer conduit, and means for sealing said hoppers when the valves are open.

In testimony whereof I affix my signature.
FREDERIC L. WARD.
